INVENTOR

Robert C. Anderson
By John A. Wineland, Jr.

ATTORNEY

UNITED STATES PATENT OFFICE.

ROBERT C. ANDERSON, OF BAYONNE, NEW JERSEY.

DESIGN FOR A TIN CAN.

SPECIFICATION forming part of Design No. 17,143, dated March 1, 1887.

Application filed January 21, 1887. Serial No. 925,042. Term of patent 11 years.

To all whom it may concern:

Be it known that I, ROBERT C. ANDERSON, a citizen of the United States, residing at Bayonne, in the county of Hudson and State 5 of New Jersey, have invented and produced a new and original Design for Tin Cans, of which the following is a specification, reference being had to the accompanying drawings, forming part thereof.

10 Figure 1 is a side view of my newly designed tin can. Fig. 2 is a plan view of the top of the same; and Fig. 3 is a sectional view of the top, taken on line *y* *y*, Fig. 2.

15 The leading features of my design consist of a perpendicularly-corrugated side and a diagonally-corrugated top.

20 A is the can, which is of rectangular form, the sides B of which are perpendicularly corrugated, substantially as represented in Fig. 1. C is a smooth marginal border surrounding the corrugations, and having a beading, D, as shown, at the top and bottom.

F is the top of the can, which is square in form and having cross-shaped corrugations G which join each other at the center. 25

What I claim is—

1. In a design for a rectangular tin can herein shown and described, the side thereof, consisting of a series of vertical parallel corrugations and a smooth marginal border surrounding the 30 corrugations.

2. In a design for a rectangular tin can herein shown and described, the side thereof, consisting of a series of vertical parallel corrugations and a smooth marginal border surrounding the 35 same, and beaded at its top and bottom, and having a top provided with cross shaped corrugations.

ROBT. C. ANDERSON.
